UNITED STATES PATENT OFFICE.

DAVID H. BELLAMORE, OF NEW YORK, N. Y., AND CARL BARTELS, OF HAMILTON, OHIO,
ASSIGNORS TO THE MOSLER SAFE COMPANY, OF HAMILTON, OHIO, A CORPOR-
ATION OF NEW YORK.

SAFE CONSTRUCTION.

Application filed May 16, 1922. Serial No. 561,454.

To all whom it may concern:

Be it known that we, DAVID H. BELLAMORE and CARL BARTELS, both citizens of the United States, residing, respectively, in the 5 borough of Manhattan, city, county, and State of New York, and in the city of Hamilton, county of Butler, and State of Ohio, have invented certain new and useful Improvements in Safe Constructions, of which 10 the following is a specification.

Our invention relates to the construction of safes, and more particularly relates to a joint or seam for use in the manufacture of safes built up of sheet metal plates and 15 drawn or rolled steel sections.

Heretofore in safe construction the joining of two adjacent parts has been accomplished by providing a U-shaped portion on one of the parts forming a groove or rabbet 20 into which the edge of the other part may be locked and welded. This U-shaped formation has been provided by bending the metal in sharp angles which tend to produce cracks. The joint thus formed is not resil- 25 ient, and should one or both of the parts become distorted or expanded as a result of being tampered with or subjected to the action of heat, the metal is apt to crack at the angles and to gap open.

30 One of the objects of our invention is to provide a safe having parts joined together in a joint or seam which is so constructed as to avoid the formation of sharp angles which would tend to produce cracks or gaps 35 during the process of manufacture, or thereafter. Another object of our invention is to provide a resilient joint or seam for firmly and permanently joining together adjacent parts of a safe, but at the same time 40 permitting a certain amount of distortion of the parts and functioning to decrease the tendency of the joined parts to produce cracks or gaps at the joint when the parts are tampered with or expanded under the 45 influence of heat. Other objects will be in part obvious and in part pointed out hereinafter.

In accordance with our invention we provide a locking rabbet or groove by means of 50 a member which is substantially U-shaped in cross section and in which the bottom portion of the U curves into its two sides, instead of fashioning this member, as formerly, in such a way that the bottom portion of the 55 U makes sharp angles with its side portions.

The edge of an adjoining safe part is adapted to be received and locked within the groove. This curved formation of the walls of the groove avoids the formation of sharp angles, thus lessening the tendency to produce cracks, and moreover provides a resilient joint which permits of a substantial degree of expansion or movement of the two joined parts without producing cracks or gaps at the joint. Obviously, this construc- 60 tion of joint may be embodied in any one of a number of different types of safe and it is to be understood that our invention is not limited to the specific embodiment illustrated in the accompanying drawings to 65 which we now refer, and in which:—

Fig. 1 represents a sectional view of a portion of a safe embodying our invention; Fig. 2 is a fragmentary view, partly in section and partly in elevation, of a safe embodying 75 our invention. Similar reference characters refer to similar parts throughout both views of the drawings.

Referring to the drawings, the safe comprises a construction which, except for the 80 joints or seams, is believed to be well known. The construction comprises an outer safe A and an inner safe B. The outer safe has outer walls 1 and inner walls 2 formed by sheet metal plates, the outer plates 1 being 85 joined to sheet metal corner boxes 3. The corner box 3, where it is joined to the margin of plate 1, is provided with an integral U-shaped portion forming a rabbet or groove 4 in which the margin of plate 1 is 90 received and locked, the opening of the U-shaped portion being presented toward the plate 1. The U-shaped portion of the corner plate 3 comprises the inner flange 5, bottom portion 6 and the outer flange 7, the 95 flanges 5 and 7 respectively comprising the two sides of the U and the connecting portion 6 curving into the two sides. The outer surface of side plate 1 is overlapped by the flange 5, as shown. The flange 7 is 100 preferably extended beyond the flange 5 and is welded near its outer end to the inner surface of the plate 1, as at 8. From the foregoing it will be readily apparent that the formation of sharp angles at the joint 105 is avoided, and, moreover, since the portion 6, which constitutes the bottom of the groove, is curved, a resilient joint is formed and a substantial degree of expansion and distortion is permitted to the plate 1 and to 110

the corner box 3 without producing cracks or gaps at the joint. Added resiliency is obtained by means of the extension of the outer flange 7 of the groove and by staggering the contact of the inner flange 5 with plate 1 in respect to the contact of the extended outer flange 7, as shown.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What we claim is:

1. In safe construction, in combination, a safe part having an inner flange and an outer flange extending beyond said inner flange and having a resilient curved bottom connecting said flanges, and a safe wall having a straight flat portion seated between said flanges, said wall portion contacting said inner flange, and contacting said outer flange at a point beyond its point of contact with said inner flange.
2. In safe construction, in combination, a flat wall member and a safe part having an inner flange and an outer flange in staggered relation and having a distended, curved, resilient, bottom portion connecting said flanges, said flanges abutting a straight flat portion of said wall member on opposite sides.
3. In safe construction, a resilient joint

formed by a safe part having an integral resilient portion substantially U-shaped in cross section, the bottom of said U-shaped portion curving into the sides thereof, and a safe wall having a straight flat marginal portion interlocking with said U-shaped portion and secured thereto in staggered contact with the sides of said U-shaped portion.

4. In safe construction, a resilient joint comprising in its construction, a corner box having a resilient, integral, marginal portion substantially U-shaped in cross-section, the bottom of said U-shaped portion curving into the sides thereof and one of the sides extending beyond the other, said U-shaped portion being adapted to receive between its sides the edge of a wall plate with the extended side of the U-shaped portion abutting against and welded to one surface of said plate and the other side of the U-shaped member abutting against the opposite surface of said plate.

This specification signed and witnessed this 3rd day of March, 1922.
